UNITED STATES PATENT OFFICE.

JOHN KNOX, OF CHATHAM, NEW JERSEY, ASSIGNOR TO DWIGHT & LLOYD SINTERING CO., INC., OF NEW YORK, N. Y., A CORPORATION OF DELAWARE.

SINTERING MACHINE.

Application filed January 15, 1926. Serial No. 81,378.

This invention relates to improvements in sintering machines of the class in which movable receptacles or pallets travel successively and continuously upon tracks over suction or wind boxes, the upper tracks being substantially horizontal and the lower tracks being substantially horizontal or inclined downwardly from the ore discharging end of the machine toward the ore charging end of the machine, sprocket wheels at the last named end of the machine operating or moving the receptacles or pallets. When such machines are relatively short, say from 20 to 30 feet long, the succeeding pallets, as delivered from the propelling sprockets, will usually arrange themselves in satisfactory position for travel along the upper tracks, because of comparatively slight pressure between the pallets. When such machines are of considerable length, say up to 60 feet long, it has been found in practice that the succeeding receptacles or pallets, because of the greater pressures between them adjacent to the pallet delivery points of the sprockets at the charging end of the machine, are liable to assume, at their meeting ends, angularly disposed or inclined positions respecting one another, in such a manner that a receptacle or pallet will engage the adjacent end of the succeeding forward pallet in an edgewise way and its forward end will not properly descend upon the track, due to the resistance of the heavily charged receptacles being propelled. Such inclined pallets then assume what is called a "cocking" position, with the forward portion of a pallet not only raised from the supporting and guiding tracks but from the wind box, which permits leakage of air into the wind box with a consequent loss of efficiency in operation of the machine. The objections above recited are due to the fact that the receptacles or pallets have been so delivered by the rear or driving sprockets as to remain in operative contact therewith so that there was not sufficient freedom at the delivery point of the sprockets for adjustment of the pallets relatively one to another before they were pushed onto the upper tracks, with a consequent "cocking" of the pallets above referred to.

The principal object of the present invention is to provide means for propelling receptacles or pallets with respect to the outer or rear portion of the driving sprockets in

such a way that the receptacles will properly adjust themselves relatively one to another, before being put under the great driving pressure necessary to move the top line of pallets, so that the receptacles or pallets will travel in proper endwise relation to each other along the upper tracks and in proper relation to the wind box, whereby efficiency and economy of operation are obtained.

Other features of the invention comprise means for movably supporting the wind box or wind boxes, as well as the dead plate at the delivery end of the machine, in such a manner that in expanding or contracting under heat changes they may move forward or backward without transmitting stresses or strains to the main frame of the machine due to heat; means for adjustably supporting the driving sprockets and the actuating gearing with respect to the tracks for the receptacles or pallets, whereby the sprockets may be retained in required set position respecting the receptacles or pallets to aid in causing the latter to be properly positioned and driven one behind another; providing the driving sprockets with one or more roving teeth so arranged that no tooth will come in a succeeding rotation in cooperation with the same projection or wheel of the receptacles or pallets; to provide the sprockets with replaceable sprocket teeth for propelling the receptacles or pallets and replaceable gears for driving the sprockets; and to provide, at the delivery end of the machine, sprocket wheels which are propelled by the traveling receptacles or pallets at the upper parts of the sprockets, and which sprockets, at their lower parts, engage empty receptacles or pallets for propelling the latter on their return to the charging end of the machine, which sprockets are automatically movable in the direction of the length of the machine to properly cooperate with the projections or wheels of the moving receptacles or pallets on the upper tracks in accordance with the expansion and contraction in a longitudinal direction of the receptacles or pallets due to heat conditions, which sprockets also serve as a registration device to insure the delivery of the pallets at the discharge end of the machine in proper relation one to the other laterally and angularly, as well as to the main driving sprockets laterally and angularly.

In the machine illustrated in the accom-

panying drawings the curved tracks at the rear of the driving sprockets for the receptacles or pallets are located at such a distance behind the sprockets, as on a curve 5 eccentric to the axis of the sprockets, that the projections or wheels of the receptacles or pallets, which are engaged by the teeth of said sprockets for propelling the receptacles or pallets, are out of contact with the 10 sprockets so that the teeth at the lower and upper portions only of the sprockets engage said projections or wheels, whereby the receptacles or pallets are propelled along said curved portions of the tracks free from 15 the sprockets, and as such receptacles or pallets are empty they will automatically seat themselves with relation one to another as they approach the horizontal portions of the tracks adjacent to the upper delivery portions 20 of the driving sprockets, so that when the adjacent teeth of said sprockets engage the aforesaid projections or wheels of the receptacles to propel them the latter will have assumed the proper end-to-end relation 25 for travel along the upper tracks.

The invention also comprises novel details of improvement that will be more fully hereinafter set forth and then pointed out in the claims.

30 Reference is to be had to the accompanying drawings forming a part hereof, wherein

Fig. 1 is a side elevation of a sintering machine embodying this invention;

35 Fig. 2 is a detail side view of one of the curved tracks;

Fig. 3 is an edge view of Fig. 2;

Fig. 4 is a perspective view of a connecting track section between the curved portion 40 and main track;

Fig. 5 is a plan view;

Fig. 5^a is an enlarged side view of gear supporting means;

Fig. 5^b is an end view of Fig. 5^a;

45 Fig. 6 is an enlarged detail longitudinal section at the receptacle propelling end of the machine;

Fig. 7 is a cross section, substantially on line 7, 7, in Fig. 6;

50 Fig. 8 is a cross section on line 8, 8, in Fig. 1;

Fig. 9 is a horizontal detail on line 9, 9, in Fig. 8;

55 Fig. 10 is a perspective view of a dead plate;

Fig. 11 is a detail of a sprocket shaft bearing at the delivery end of the machine; and

60 Fig. 12 is an end view of Fig. 11, partly in section.

Similar numerals of reference indicate corresponding parts in the several views.

The main frame of the machine is indicated at 1 and may be of any suitable or

usual construction, being shown provided 65 with horizontally disposed upper tracks 2 and lower tracks 3 which are shown inclined downwardly from the discharge end toward the ore receiving and receptacle propelling end of the machine. The tracks 70 may be supported on the main frame in any suitable way. At 4 are receptacles or pallets of any usual or suitable construction, shown of the class provided with removable perforated grate bars 5. The receptacles or 75 pallets are shown provided with pairs of spaced laterally projecting flanged wheels 6 on opposite sides, adapted to support and guide the receptacles upon and along the tracks of the machine in an ordinary way. 80 At the ore receiving and receptacle propelling end of the machine driving sprocket wheels 7 are spaced apart and secured upon shaft 8 which is journaled in bearings 9, having suitably secured caps 9^a, supported 85 by the main frame, (Figs. 5^a and 7). The upper track 2 commences adjacent to the dead plate 10 secured upon the main frame, at the charging end of the machine, (Fig. 6), and rearwardly from the dead plate, in 90 the direction of the sprockets 7, extend upper track sections 11 upon which the wheels or side projections of the receptacles or pallets 4 travel to the dead plate as propelled by the upper delivery portions of the 95 sprockets 7, which, as shown, engage the projections 6^a of the receptacles or pallets, (Figs. 6 and 7). The lower tracks 3, at their lowest points, terminate adjacent to the lower portions of the sprockets 7, at the 100 lower track sections 11, in such a manner that the lower teeth of said sprockets will engage the projections 6^a of the lower receptacles to propel the latter. Tracks 12 extend rearwardly behind the sprocket 105 wheels 7 and are spaced apart to receive the wheels 6 of the receptacles, which tracks are curved, the lower ends of said tracks coinciding with the lower track sections 11, and the upper ends of said tracks 12 coincide 110 with the adjacent ends of the upper track sections 11, in such a manner that the wheels 6 of the receptacles will engage the tracks 12 to be guided thereby while free from the sprocket wheels for delivery to the upper 115 track sections 11, (Figs. 1 and 6). The tracks 12 have spaced concentrically disposed lateral webs or webs 12^a, 12^b, (Figs. 2, 3 and 7), between which the wheels 6 of the receptacles travel so as to be guided and be retained in the curved tracks 12, the wheels 6 at one time riding upon the lower portions of webs 12^a and at another time riding up to and along the upper portions of the webs 12^b for delivery to the track sections 11. The tracks 12 are located on a curve spaced 120 from and eccentric to the axis of sprockets 7, whereby the wheels 6 are kept out of con-

tact with the driving or propelling sprockets 7 between the lower and upper engaging portions of the latter.

By means of the arrangements described 5 the lower receptacles or pallets 4 are pushed by the lower portions of the sprockets 7 along the curved tracks 12, and as said receptacles at such time are empty they only 10 present the resistance of their own weight without a load. During the travel along tracks 12 the receptacles assume angular positions relatively one to another but do not force the receptacles that are upon the upper tracks 2. When the receptacles have been 15 pushed around tracks 12 and delivered on upper track sections 11 to the point where the upper portions of sprockets 7 engage the projections 6^a of the receptacles, the latter are successively pulled for a distance completely free from each other, and during 20 such period assume by gravity their proper positions with regard to upper track sections 11 and the pallet immediately in advance which is being driven by the sprockets and which in turn drives the line ahead 25 across the dead plate 10 and along the tracks 2.

The sprockets 7 have an uneven number of roving teeth, whereas the receptacles or 30 pallets 4 have an even number of projections 6^a on each side, whereby when said sprockets rotate each time no sprocket tooth will a second time and successively come in coaction with the same projection 6^a of a 35 receptacle or pallet, and, therefore, since given sprocket teeth will not re-engage the same projections 6^a of the receptacles or pallets for a number of rotations of the sprocket teeth wear on the sprocket teeth 40 will be reduced and the life of the sprockets will be correspondingly increased.

The wind box or boxes 14 may be supported on the main frame in position below the tracks 2 in any desired way and in a 45 well known manner for cooperation with the receptacles or pallets 4 so that air may be sucked through the ore in said receptacles into the wind box to support combustion of the ore in the receptacles. An outlet opening 50 15 in the wind box, (Fig. 1), may be connected with a suitable air exhaust apparatus in any desired way. There may be one or more of such wind boxes, as usual in the class of machines referred to.

55 In the example illustrated there are provided a series of wind box sections or castings 14^a, secured together side by side, as by rivets *a*, (Figs. 1, 8 and 9), which sections or castings are slidably supported upon longitudinal bars 1^a, that extend along opposite sides of main frame 1, said sections having ledges 14^b resting on the bars 1^a. A shell 14^c is riveted at *b* to the sections 14^a and has closed ends at 14^d, (Figs. 6 and 8), 60 forming a lower closed portion of the wind

or suction box, the opening 15 being suitably provided in said shell. Flexible sealing strips *c* extending along the wind box and in engagement with the pallets or receptacles 4, as they slide over the wind box, 70 serve to resist inflow or leakage of air into the wind box along the receptacles, (Fig. 8). The forward dead plate 10^a, (Fig. 5), is secured to the adjacent forward wind box section 14^a, which dead plate slidably rests 75 upon the side bars 1^a. Since the rear dead plate 10 is secured to main frame 1 and the wind box and the dead plate 10^a are slidably supported by the said frame it follows that the wind box or boxes and the 80 dead plate 10^a, in expanding or contracting under heat changes may move forward or backward freely along the main frame 1 without transmitting stresses or strains to said frame due to heat conditions transmitted to the wind box by the heated ore on the receptacles or pallets 4.

The sprocket wheels are shown comprising wheels 7^a having toothed rings 7^b secured thereto, as by rivets, said rings being set in annular recesses 7^c in said wheels and bearing laterally against annular flanges 7^d thereof, (Fig. 7), whereby the sprocket rings may be replaced when required. The sprockets 7 may be rotated in any desired 90 way, as by means of gears 16, shown detachably secured by means of rivets to the wheels 7^a, (Fig. 7), said gears being in mesh with pinions 17 secured upon shaft 18 journaled in suitable bearings supported upon the main frame, (Figs. 1, 5 and 6). The function of shaft 8 is to support the sprockets, either or both of which may be keyed to said shaft, and properly spaced apart by collar 8^a and key 8^b, (Fig. 7). The shaft 100 18 may be driven in any desired manner. Since it may be desirable to adjust the sprocket wheels 7 in the direction of the length of tracks 2 and 3, the bearings 9 for shaft 8 and the bearings 18^a for shaft 18, 105 at opposite ends of said shafts, are secured upon bars 19, (Fig. 5^a), that are slidably supported upon the longitudinally disposed saddles 19^a that are secured upon spaced beams 1^b of frame 1, (Fig. 7). The beams 110 1^b are shown in the form of channel-beams with their flanges spaced apart to receive the longitudinal rib 19^b of the corresponding saddle 19^a, whereby said saddles are retained from lateral displacement upon the beams 1^b. The bars 19 may be adjusted longitudinally and retained in set position by means of screws 20 operative in lugs 21 secured on saddles 19^a, which screws oppose the ends of bars 19, (Fig. 5^a), whereby when 115 said screws are rotated and the bars 19 adjusted the shafts 8 and 18 will be correspondingly adjusted so that the sprocket wheels 7 may be placed in set position to cause their teeth to properly cooperate with

120
125
130

the projections 6^a of the receptacles 4, and whereby such adjusting of the sprocket wheels makes provision for properly operating receptacles 4 according to wear, heat and other conditions. The bars 19 may be retained in set positions by means of screws 22 operative in slots 23 in the bars, (Fig. 5), and working in threads in the saddles 19^a. The latter may be kept from longitudinal displacement by means of lugs 19^c, (Fig. 5^a), nested in recesses in the beams 1^b. While shaft 18 may be driven in any desired way said shaft is shown provided with spaced gears 24 in mesh with pinions 25 carried by a drive shaft 26 journaled in bearings 27 carried by the bars 19, so that when said bars are adjusted longitudinally the gearing 16, 17, 24 and 25, with their shafts will be adjusted while retaining the relative positions. By having the spaced pinions 25 meshing with the spaced gears 24, and the spaced pinions 17 meshing with the spaced gears 16, torsional or angular strains are reduced and driving of the receptacles 4 is equalized on opposite sides. To equalize driving torque and avoid torsion on shaft 26 the latter is provided with a substantially centrally disposed gear 28, (Figs. 1, 5 and 6), that is in mesh with a drive pinion 29 secured on a shaft 30 journaled in suitable bearings on the main frame. Shaft 30 may be driven by any desired means, shown as reducing gearing 31, 32, 33, 34, 35, driven by pulley 36, (Fig. 5), or in any suitable way. The construction described enables equal driving of sprockets 7 and avoids unequal movements of the various parts due to torsional action.

At the discharge end of the machine tracks 40 are provided at 12^c leading from the adjacent ends of tracks 2 to the receiving ends of the tracks 3. The tracks 12^c are preferably of the same construction as the tracks 12, so that the outer and inner webs 12^a, 12^b 45 guide the wheels 6 of receptacles 4 to travel from the upper tracks 2 to the lower tracks 3, whereby the receptacles are turned upside down and their contents dumped. Adjacent to the forward or discharge ends of tracks 2 50 and 3 spaced sprocket wheels 37 are secured upon shaft 38, (Figs. 1 and 5), in such a position that the teeth of said sprocket wheels at the upper portion will engage the projections 6^a of the receptacles 4 to cause 55 rotation of the sprockets by reason of the travel of the receptacles, and when the receptacles are upon the lower tracks 3 the projections 6^a will engage the lower teeth of the said sprockets to cause propulsion of the empty receptacles 4 along the lower tracks 3 to aid the receptacles in their travel toward the driving sprockets 7 additionally to the tendency of the receptacles to travel along the downwardly inclined tracks 3 by gravity. 60 The shaft 38 is shown supported to have lat-

eral movement, in the longitudinal direction of the machine, automatically in accordance with the heat conditions of the receptacles or pallets 4. The shaft 38 is shown supported in bearing boxes 39, (Figs. 1 and 11), that are slidably supported on guides 40 secured upon the main frame, such guides being shown comprising castings having bases 40^a provided with spaced abutments 40^b between which the bearing boxes are mounted to slide 75 under caps 41 secured upon the abutments. The bearing boxes 39 have upper and lower grooves 42 receiving the bases 40^a and caps 41, respectively, the flanges of the boxes being located on opposite sides of said bases 80 and caps, whereby the boxes are slidable and are retained from lateral displacement. The boxes are connected with rods or links 42 pivotally connected at 43 with levers 44 pivotally supported at 45 upon the main frame, 85 (Figs. 1 and 5). The free ends of the levers 44 are connected to chains 46 which pass over pulleys 47 journaled upon the main frame and weights at 48 depend from the chains, whereby the shaft 38 and its sprockets 37 are normally automatically drawn toward the charging end of the machine. By having bearing boxes with levers and weights or their equivalent on opposite sides of the machine for the respective ends 90 of shaft 38 the latter will be substantially equally drawn by the weights, as distinguished from variable tension if springs were used instead of weights. When the projections 6^a of the receptacles or pallets 95 that are being propelled on tracks 2 engage the upper teeth of the sprocket wheels 37 said receptacles or pallets will cause the sprocket wheels to rotate, and when the receptacles or pallets have passed beyond said 100 sprocket wheels and descend along the curved tracks 12^c to the lower tracks 3, the teeth at the lower portions of the sprocket wheels will engage the projections 6^a of the receptacles or pallets and serve as a return 105 drive for the latter along the tracks. When the receptacles or pallets 4 elongate in length upon tracks 2, due to expansion of the receptacles or pallets by reason of heat conditions, they may, by cooperation with the sprocket wheels 37, cause displacement of 110 said sprocket wheels in the longitudinal direction of the machine toward the delivery end of the latter, such sprockets being resisted by the weights 48. Upon contraction of the length of the receptacles or pallets, due to other heat conditions, the weights 48 115 will tend to draw the sprockets from the delivery end of the machine. By the means described the said sprockets automatically 120 are adjusted to accommodate the projections 6^a of the receptacles or pallets as may be required for uniform operation of the sprockets, and thereby strain through the 125 sprockets from the receptacles or pallets to 130

the main frame is reduced, and improved results are obtained over the previous practice of having the upper pallets drive sprockets journaled in non-movable bearings. The sprockets 37 are not only a return pallet drive but are also a registration device which insures the delivery of the pallets in proper relation one to the other laterally and angularly, and to the main drive sprockets 7 laterally and angularly.

By means of the improvements described sintering machines of the class specified, of considerable length, say, 60 feet or more long, may be provided, whereby assurance will be had that the receptacles or pallets will be applied upon the upper horizontal tracks 2 in proper successive order, engaging one another end-to-end in the required relationship, without the necessity of providing any bars, springs or other devices, as have heretofore been used, to cause the receptacles to adjust themselves in proper relative positions against one another at or adjacent to the propelling sprockets 7 to avoid "cocking" of the receptacles before referred to, whereby the cost of operating the machine is reduced and more uniform sintering of the ore is assured.

Having now described my invention what I claim is:—

1. An ore treating machine comprising upper and lower tracks for receptacles, means to propel the receptacles along the upper tracks, and curved tracks for said receptacles adjacent to and spaced from said propelling means to maintain said receptacles out of engagement with said propelling means during travel of the receptacles along said curved tracks.

2. An ore treating machine as set forth in claim 1, in which the curved tracks comprise spaced outer and inner ways, the outer ways being adapted to receive the receptacles on the lower tracks and the inner ways being adapted to deliver the receptacles to the upper tracks.

3. An ore treating machine comprising upper and lower tracks for receptacles, sprocket wheels to propel said receptacles along the upper tracks, and curved tracks spaced from said sprocket wheels and located in position to receive the receptacles from the lower tracks and deliver the receptacles to the upper tracks, whereby the receptacles will be out of engagement with the sprocket wheels during travel along said curved tracks.

4. An ore treating machine comprising upper and lower tracks for receptacles, means to propel the receptacles along the upper tracks, and curved tracks for said receptacles located in position to receive receptacles from the lower tracks and deliver the receptacles to the upper tracks, said curved tracks being located behind the propelling

means and eccentric thereto to guide the receptacles out of engagement with the propelling means.

5. An ore treating machine comprising a frame, upper and lower tracks for receptacles, means to guide the receptacles from the lower to the upper tracks, sprocket wheels to propel said receptacles to and along said upper tracks, gears connected with the sprocket wheels for rotating them, pinions for actuating said gears, a shaft carrying said pinions, bars movably carried by said frame for adjustment in the direction of travel of the receptacles, bearings for said sprocket wheels, gears and pinions supported by said bars to maintain them in cooperative relation, an adjustment of the bars correspondingly setting the sprocket wheels for desired cooperation with the receptacles, and means to retain said bars in set position.

6. An ore treating machine as set forth in claim 5, in which the shaft for the pinions is provided with a gear located between said pinions, and means for rotating said gear.

7. An ore treating machine comprising a frame, upper and lower tracks for receptacles, means to guide the receptacles from the lower to the upper tracks, sprocket wheels to propel said receptacles to and along said upper tracks, gears connected with the sprocket wheels, gearing to rotate said gears, movable bars carrying said sprocket wheels and gearing and adjustable lengthwise of said frame, said bars maintaining the sprocket wheels and gearing in cooperative relation, saddles supporting said bars and provided with lugs adjacent to the ends of said bars, and screws carried by said lugs and cooperative with said bars to adjust them longitudinally, an adjustment of the bars correspondingly setting the sprocket wheels for desired cooperation with the receptacles.

8. An ore treating machine comprising upper and lower tracks for receptacles, means to propel the receptacles along the upper tracks from the charging end of the machine, means at the delivery end of the machine to guide the receptacles from the upper to the lower tracks, laterally movable sprocket wheels at the delivery end of the machine to be operated by the receptacles, and means movably resisting said sprocket wheels in the longitudinal direction of the machine to accommodate expansion and contraction of the receptacles due to heat conditions.

9. An ore treating machine as set forth in claim 8, in which the sprocket wheels are provided with movable bearings, guiding means for said bearings, and retracting means for said sprockets and bearings.

10. An ore treating machine comprising upper and lower tracks for receptacles, means to propel the receptacles along the

- upper tracks, and curved tracks for said receptacles located in position to receive receptacles from the lower tracks and deliver the receptacles to the upper tracks, curved tracks at the opposite ends of the upper and lower tracks located in position to receive receptacles from the upper tracks and deliver them to the lower tracks, laterally movable sprocket wheels journaled adjacent to the last named curved tracks, and means movably resisting said sprocket wheels in the longitudinal direction of the machine to accommodate expansion and contraction of the receptacles due to heat conditions.
15. 11. An ore treating machine comprising a frame, upper and lower tracks for receptacles, means to propel the receptacles along the upper tracks, a wind box below the upper tracks, and means slidably supporting the wind box on said frame.
20. 12. An ore treating machine as set forth in claim 11, in which one end of the wind box is connected to the frame whereby the wind box may elongate and contract longi-

tudinally of the frame due to varying heat 25 conditions.

13. An ore treating machine comprising a frame, upper and lower tracks for receptacles, means to propel the receptacles along the upper tracks, a wind box slidably supported by the frame, and a dead plate attached to each end of the wind box, one of the dead plates being attached to the frame and the other dead plate being slidably supported on the frame. 30 35

14. An ore treating machine comprising a frame, means to support receptacles for travel along the frame, means to propel said receptacles, and a wind box carried by said frame, said wind box including a plurality 40 of sections side by side and a shell connected at its upper portion to said sections and depending below the same.

15. An ore treating machine as set forth in claim 14, in which dead plates are located 45 at the ends of the wind box, and means supporting the dead plates on the frame.

JOHN KNOX.
